WALTER S. ROCKWELL, OF NEW YORK, N. Y., ASSIGNOR TO W. S. ROCKWELL COMPANY, OF NEW YORK, N. Y., A CORPORATION OF NEW JERSEY.

SECTIONAL LINING FOR ROTARY FURNACES.

1,330,219.

Specification of Letters Patent. Patented Feb. 10, 1920.

Application filed September 8, 1919. Serial No. 322,572.

To all whom it may concern:

Be it known that I, WALTER S. ROCKWELL, a citizen of the United States, residing at 300 West 106th street, New York, county 5 of New York, and State of New York, have invented certain new and useful Improvements in Sectional Linings for Rotary Furnaces, fully described and represented in the following specification and the accompanying drawings, forming a part of the same.

The present invention relates to an improved means of providing a cylindrical rotary furnace with an interior spiral rib, to produce a spiral channel for automatically 15 conveying the material to be heated from one end of the furnace to the other when the furnace is rotated.

A furnace of this class lined with fire-brick and provided with means for automatically conveying the material through 20 the furnace-chamber is shown in my Patent No. 940,280, issued November 16, 1909, the spirally disposed rib being formed therein of clay-tile, inserted between the courses of 25 the brick-lining.

With such construction, the material rolls or slides continuously upon the surface of the highly heated brick-lining in contact with the tile-rib, and as the material to be heated may 30 consist of iron, steel or other metallic articles, they necessarily abrade the surface of the tile and cause such a deterioration that the lining and rib require frequent renewal.

The object of the present invention is to 35 avoid such rapid deterioration, and this is effected by applying a metallic shell to the inner surface of the brick or other refractory lining, and forming the spiral rib integral with such metallic shell.

To facilitate the application of such metallic shell to the interior of the furnace lining, it is formed in short cylindrical sections each provided preferably with one complete coil of the spiral rib, the sections 45 being so arranged when applied to the furnace as to form a continuous spiral rib upon the inner side of the shell.

Such furnaces are highly heated by gas or oil fuel and the shell thus protects the brick-lining from too destructive heat and abrasion, and the ribs projecting from the shell 50 form a spiral channel the walls of which are formed wholly of metal, and thus enabled better to resist the abrasive action of

the stock in its movement through the channel as the furnace rotates. 55

If the sections of the inner shell were made with plane ends the joint of the ribs would be necessarily formed with thin tapering edges which would be subject to rapid wear 60 and fracture; and to avoid this result one-half of each end of the sections is offset directly across the terminal of the coil and thus intersects the rib transversely nearly at right-angles; which preserves the entire 65 strength of the coils where the ends are matched and abutted together.

The sections may obviously be provided with more than one coil of the ribs, but the formation of the sections by casting is 70 greatly facilitated by forming them with only one coil, and the entire inner shell of the brick lining can thus be formed of uniform sections excepting at the extreme ends, where the brick-work and its shell extend 75 to the inlet and outlet of the furnace.

Sections of special form are required at these points, as will be understood by reference to the annexed drawing, which shows the rotary body of the furnace provided 80 with a stationary hood at its outlet-end and an annular steam-chamber attached to the shell of the furnace to maintain a steam-atmosphere over the joint of the furnace and hood, so as to prevent the access of air which 85 might oxidize the heated articles of the stock as they are discharged from the furnace.

In the drawing, Figure 1 is a longitudinal section of a rotary furnace having its body rotated contiguous to a stationary head at 90 the delivery-end; Fig. 2 shows in longitudinal vertical section the sections of shell at the left-hand end of the furnace; Fig. 3 shows the same sections of shell divided horizontally upon the center line; Fig. 4 95 shows the outlet-end of the furnace with its steam-chamber and a part of the contiguous hood; and Fig. 5 shows the outlet-end of the furnace-body with the hood removed, thus exposing the interior of the steam-chamber. 100

The furnace is shown with a cylindrical shell 1 having a brick-lining 2. A conical hopper or feeding-drum 3 is attached to the inlet-end into which the material *a* is delivered, as in my Patent No. 940,280. The material enters one end of the channel 4, which is formed by the spiral rib 5, upon

the interior of the cylindrical sections 6 which form a protective shell for the brick-lining 2.

Fig. 1 shows four similar sections of the 5 cylindrical shell, each provided with one coil of the rib 5; and end-sections of special character. The four sections have their opposite ends offset in opposite directions so as to intersect respectively the opposite ends 10 of the coils on such sections. These sections are so proportioned that when their offset ends are matched or abutted together the successive coils of the rib form a continuous rib and a continuous spiral channel 15 upon the inner side of the furnace-chamber. Each offset forms a division in the rib.

The end-sections are offset upon one end only, the opposite end being plane in agreement with the flanges 7 which are attached 20 to the inlet and outlet-ends of the shell.

These end-sections are provided with more or less than one coil of the rib, which at one end joins the coils upon the adjacent sections, and at the opposite end is so disposed as to receive the material from the 25 feeding-drum, or discharge it from the outlet 8 of the furnace.

If the end-sections be made of equal length, the same pattern can be utilized for 30 casting both the sections, but they would be applied to the intervening sections in a reverse relation, as is clearly shown in Fig. 1.

The left-hand end of Fig. 1 shows the 35 stock in the form of round balls entering the channel 4, and the right hand end shows such balls in the bottom of the channel at the outlet, where they would be pushed gradually into the hood 9 by the end of the 40 coil shown in the upper part of the outlet 8.

The casing is formed as usual with annular bearing-rings 10 supported upon anti-friction rolls 11, and is rotated by any suitable means.

The hood is stationary and is provided at its bottom with a chute 20, and upon its inner side with a circular plate 12 contiguous to the end of the casing, and extends 50 outwardly beyond the periphery of the casing sufficiently to close the mouth of an annular steam-chamber 13 built upon the outlet-end of the casing.

It is evident that no close joint can be 55 maintained between the end of the casing and the hood, and air would be liable to penetrate through an open joint and cause oxidation of the articles heated in the furnace in their passage to the chute. To prevent such intrusion of air is the function of the steam-chamber referred to.

The steam-chamber is open on the side toward the plate 12, which extends beyond the periphery of the steam-chamber sufficiently 65 to sustain a guard-ring 14, which is

shown in the form of an angle-iron, one flange of which is attached to the plate 12 and the other flange overlaps the periphery of the steam-chamber.

A steam-pipe 15 is inserted through the 70 overlapping flange of the guard to keep the steam-chamber filled with steam, which thus flushes and protects the joint between the revolving casing and the hood from any intrusion of air. The use of steam for 75 thus closing the joint produces no frictional resistance to the rotation of the casing, while it protects the joint effectively.

A burner-inlet 16 is shown upon the hood above the chute, and a burner 17 is located 80 at such inlet and its nozzle directed lengthwise of the furnace-chamber so as to drive the flame throughout its entire length.

The chute may be operated in any usual manner, as to discharge the material into 85 any suitable receptacle or into a quenching tank. The nozzle of the chute may, if desired, be sealed by extending it under the surface of a liquid so as to quench the articles before they are at all exposed to the 90 atmosphere.

Having thus set forth the nature of the invention what is claimed herein is:

1. A cylindrical rotary furnace having a refractory lining and sections of a metallic 95 shell fitted endwise within the said lining and provided each with one or more spiral coils of an inwardly projecting rib, the cylindrical sections being so disposed within the lining as to arrange the several single 100 coils in a continuous spiral line throughout the length of the furnace, to form a spiral channel therein with entirely metallic walls.

2. A cylindrical rotary furnace having a refractory lining and sections of a metallic 105 cylinder fitted endwise within the said lining and provided each with a spiral coil, and the opposite ends of each section offset in opposite directions to form a division across the spiral rib at each end of the 110 section.

3. A cylindrical rotary furnace having a refractory lining and a series of metallic shells of cylindrical form fitted endwise within the said lining and provided each 115 with a spiral coil of inwardly projecting rib terminating at opposite ends of the section, the ends of the section being offset in opposite directions transverse to the ends of the said coil, and the ends of the sections 120 being suitably matched together within the lining to form a continuous spiral rib and channel and a continuous covering for the lining between the spiral ribs.

4. A rotary furnace having a refractory 125 lining and an inlet revolved therewith at one end and an outlet revolved therewith at the opposite end, a stationary hood having a chamber connecting with the said outlet and provided with a delivery-chute, and 130

a spiral rib upon the lining of the shell forming a conveying channel from the inlet to the outlet and extended close to the hood to deliver the material positively to the 5 chamber therein.

5. A rotary furnace having a cylindrical casing with refractory lining and an inlet revolved therewith at one end and outlet revolved therewith at the opposite end, a 10 stationary hood having a chamber connecting with the said outlet and having a delivery-chute extending from its lower side, and a burner-inlet upon its outer side with a burner projected toward the bore of the 15 furnace to heat the same.

6. A rotary furnace having a cylindrical casing with refractory lining and an inlet revolved therewith at one end and an outlet revolved therewith at the opposite end, a 20 stationary hood having a chamber connecting with the said outlet and provided with a delivery-chute, an annular steam-chamber encircling the joint of the cylindrical shell with the hood, and means for supplying 25 steam to the same to flush the said joint and prevent the access of air thereto.

7. A rotary furnace having a cylindrical casing with refractory lining and an inlet

revolved therewith at one end and an outlet revolved therewith at the opposite end, a 30 stationary hood having a chamber connecting with the said outlet and provided with a delivery-chute, an annular flange upon the hood overlapping the adjacent end of the steam-chamber, and a steam-pipe extended 35 through the flange to flush the joint of the casing and hood, for the purpose set forth.

8. A rotary furnace having a cylindrical casing with refractory lining and an inlet revolved therewith at one end and an outlet 40 revolved therewith at the opposite end, a stationary hood having a chamber connecting with the said outlet and provided with a delivery-chute, a circular plate upon the hood opposed to the end of the cylindrical 45 shell, an annular steam-chamber upon the casing opening toward the said plate over the joint of the casing and plate, and an annular flange upon the plate covering the joint of the steam-chamber and plate, and 50 means to supply steam through the said flange to the interior of the steam-chamber.

In testimony whereof I have hereunto set my hand.

WALTER S. ROCKWELL.
